UNITED STATES PATENT OFFICE.

ARTHUR JAMES TIZLEY, OF BROOKLYN, NEW YORK, ASSIGNOR TO EDWARD F. CALDWELL & CO., INC., OF NEW YORK, N. Y., A CORPORATION OF NEW YORK

ADJUSTABLE BRACKET FOR LAMPS.

Application filed January 19, 1927. Serial No. 162,166.

My invention has for its object to provide an adjustable bracket which may be used for lamps and other purposes, the bracket being cheap to construct, artistic in appearance, and so constructed that it will permit of the convenient replacement of the bracket arm and lamp when desired. The bracket arm which may be replaced when desired is held in an adjustable position on a standard by cylindrical members to which it is detachably secured and which enclose the mechanism for holding the bracket arm and cylindrical members in adjusted position on the standard.

Additional objects of the invention will appear in the following specification in which the preferred form of construction of the invention is disclosed.

In the drawings similar reference characters refer to similar parts in all the figures, in which—

Figure 1 is an elevation showing my invention;

Fig. 2 is an enlarged sectional view on the line 2—2 of Fig. 1;

Fig. 3 is a sectional view similar to that shown in Fig. 2 showing the parts in position when the bracket is moved upwardly on the standard; and

Fig. 4 is another sectional view similar to that shown in Fig. 2 but illustrating the parts in the position which they will assume when the bracket is being adjusted downwardly on the standard.

By referring to the drawings it will be seen that on the standard 5 there is disposed a collar 6 to which is secured a woven metal tubular member 7 to the upper end of which there may be secured a band 8 which fits snugly the standard 5. Mounted on the collar 6 and enclosing the woven metal tubular member 7 there is a coil spring 9 and enclosing the coil spring 9 and the woven metal tubular member 7 there are cylindrical members 10 and 11. The upper cylindrical member 10 has an outer head 12 with which the upper end of the coil spring 9 engages. The lower cylindrical member 11 has a head 13 on which the collar 6 normally rests. The inner or lower end of the upper cylindrical member 10 has threads 14 and the inner or upper end of the lower

cylindrical member 11 has threads 15 with which meshes the threads 16 on the bracket 17.

The bracket 17 has a collar 18 in which the lamp arm 19 is secured by any suitable means.

The woven metal tubular member 7 fits snugly the standard 5 and serves to support the cylindrical members 10 and 11 and the bracket 17 in adjusted position on the standard 5. When it is desired to raise the cylindrical members 10 and 11 with the bracket 17 this may be done by moving upwardly the cylindrical members 10 and 11 and the bracket 17, for with this upward movement the woven metal tubular member 7 will be slightly compressed which will increase the diameter of the woven metal tubular member 7 and reduce the friction between the woven metal tubular member 7 and the standard 5. The band 8 will assist in this inasmuch as the said band 8 fits closely the standard 5 and serves to retard the upward movement of the woven metal tubular member 7, thereby compressing the woven metal tubular member 7 and extending its diameter but this band 8 does not fit the standard 5 closely enough to interfere with this upward movement.

When it is desired to lower the bracket 17 on the standard 5 the cylindrical members 10 and 11 with the bracket 17 are pressed downwardly which will move the head 12 on the cylindrical member 10 against the band 8 and serve to compress the woven metal tubular member 7 which will free the woven metal tubular member 7 sufficiently from the standard 5 to permit of the downward movement of the bracket 17 on the standard.

I claim:

In an adjustable bracket, a standard, a woven metal tubular member mounted on the standard, a collar on the standard secured to the lower end of the woven metal tubular member, a coil spring disposed around the woven metal tubular member and resting on the collar, two cylindrical members disposed one above the other enclosing the spring and having heads at their outer ends, the upper end of the spring engaging the head on the upper cylindrical

member with the upper end of the woven metal tubular member normally spaced from the head on the said upper cylindrical member, the head on the lower cylindrical member being disposed under the collar for engaging the latter, the cylindrical members having threads at their inner ends, and a

lamp carrying bracket having a collar disposed on the standard at the inner ends of the cylindrical members, the collar being provided with threads meshing with threads on the cylindrical members. 10

ARTHUR JAMES TIZLEY.
